PACKAGE FOR DISPENSING PAPER SHEETS

Filed June 22, 1936

UNITED STATES PATENT OFFICE

2,165,107

PACKAGE FOR DISPENSING PAPER SHEETS

Albert R. Lawson, Hamilton, Ontario, Canada,
assignor to Appleford Paper Products, Ltd.,
Hamilton, Ontario, Canada

Application June 22, 1936, Serial No. 86,549

4 Claims. (Cl. 206—57)

This invention relates to an improved package for dispensing sheets of paper, such as sheets of waxed paper, individually and as they are desired for use.

5 The package is so constructed and the sheets to be dispensed are so arranged therein that a large number of superimposed sheets of paper are supported within the package in such a manner that individual sheets may be readily withdrawn 10 for use and the remaining sheets are protected against exposure, soiling, or disturbance during withdrawal of sheets for use.

An object is to provide such a package wherein the container or enclosure is simple, inexpensive, 15 and convenient. The package is so formed that the container may be hung upon a wall in a position convenient for use for removal of individual sheets therefrom.

A meritorious characteristic is that the 20 container is fashioned in the form of an envelope having an opening adjacent to the top for withdrawal of the sheets therefrom and the sheets are so supported in folded form therein as to be grasped along their folded portions for withdrawal.

25 The container is self-closing following withdrawal of a sheet therefrom. Sheets which have been withdrawn but not used may be readily replaced within the container for later withdrawal.

30 The sheets to be dispensed are so supported within the package that they may be withdrawn without tearing or mutilation. The container occupies a minimum amount of space and is of maximum simplicity. The container effectively 35 protects the sheets which it carries against exposure. The package is easily fabricated and lends itself to display advertising.

Other objects, advantages, and meritorious features will more fully appear from the following description, appended claims, and accompanying drawing, wherein:

Figure 1 is an elevation of my improved package partly broken away,

Fig. 2 is a vertical sectional view taken on 2—2 45 of Fig. 1,

Fig. 3 is an elevation of a modified form of support for the sheets to be dispensed,

Fig. 4 embodies my invention in a modified form of construction, and

50 Fig. 5 illustrates my invention in a second modified form of construction.

In the dispensing of sheets of waxed paper it is common practice to provide a boxlike container within which the sheets may be disposed or to 55 provide a container within which a roll of waxed

paper is carried for withdrawal of paper from the roll and severance of a sheet therefrom. Waxed paper sheets are also packaged within a container adapted to be hung upon a wall for withdrawal of individual sheets such as illustrated in the patent to Silbar, No. 1,662,080. In this type of construction it is common practice to stitch the sheets within the container and to withdraw individual sheets tearing them from the stitching which supports them.

5 My improved package comprises a container in the form of a pocket or envelope which has a front wall 10 and a rear wall 12. These walls are connected together as illustrated to form what might be termed a pocket like enclosure open adjacent to the top for withdrawal of sheets from the pocket. This top opening is normally covered by a flap 14 here shown in the form of an end flap. The front and back wall might be made of a single sheet or two sheets pasted together as at 15 20 25 30 35 40 45 50 a single sheet or two sheets pasted together as at 15 as shown in Fig. 2. In this figure the flap is shown as an extension of the rear wall 12. An eyelet 16 extends through the flap and rear wall and holds them together at the top and provides means whereby the package may be hung up on a wall hook or the like.

Within the interior of the envelope there is provided sheet supporting means. In Fig. 2 this is shown in the form of an insert or blank 18 which extends transversely across the top of the 30 envelope within its interior and is held in place between the flap and the rear wall by the eyelet 16. This blank is cut away as at 20 and the cut out portion may be folded downwardly as at 22 to provide a rounded supporting edge upon which 35 the sheets for withdrawal are suspended.

A large number of superimposed sheets 24 are folded upon themselves over this rounded edge portion 25 and so supported within the envelope that the folded edge portions of the sheets are 40 opposite the opening provided in the envelope for withdrawal. The front wall 10 will be cut away as at 26 to facilitate grasping of individual sheets for withdrawal from the envelope and as shown in the figures of the drawing. It will appear 45 that the sheet supporting edge portion of the sheet carrier is disposed slightly above the bottom of the pocket opening in the envelope through which sheets are withdrawn. This facilitates the grasping of the folded portions of 50 the sheets for withdrawal.

In Fig. 3 there is illustrated a hanger or sheet carrier 28 formed of wire shaped as shown to be inserted within the envelope. This wire is bent to provide a small loop 30 which may encircle 55

the rivet 16 for suspension of the hanger within the envelope. In Fig. 4 the sheets 24 are shown as folded over a relatively rigid card 32 which card seats within the envelope and supports the 5 sheets 24 upon its upper edge.

In Fig. 5 the sheet supporting member is in the form of a strip 34 extending transversely across the interior of the envelope and supported therein by stitches 36 through its ends. The 10 sheets 24 are folded thereover. In this figure the flap 38 may be formed of the paper sheet which has been strengthened by chemical treatment or is so fashioned that it normally tends to yieldingly engage the front wall of the enclosure so 15 as to closely cover the pocket opening through which sheets are withdrawn therefrom. This flap is shown as secured by a band of adhesive 40 to the envelope proper. It might be secured thereto in any suitable fashion. The front and back walls 20 of the envelope may be secured together as by the flap shown in Fig. 1 being adhesively secured in place or it may be formed in any fashion well known in the manufacture of envelopes. The wall structure may be of strong, tough, relatively 25 thin flexible paper or formed of a paper sheet of any desired strength, resiliency, and thickness. The sheets may be single sheets folded once transversely for suspension over the sheet supporting element or the sheets may first be folded 30 along a longitudinal median line and then folded transversely over the sheet supporting means. In the latter instance the entire package would have a less width than if the sheets were folded merely once along a transverse line.

35 Various modifications of the invention may be carried out all within the scope of the claims. The device lends itself to simplicity of manufacture and is simple and inexpensive. It is adaptable to permit ready withdrawal of the 40 sheets and support them at all times protected against exposure.

What I claim is:

1. A dispensing package for paper sheets comprising a flat bag like structure having marginally 45 connected front and rear walls and provided with a sheet withdrawal opening extending transversely across said front wall adjacent to the top, a sheet supporting element in the form of a sheet structure secured between the said front and 50 rear walls within the bag at the top of the bag and depending within the bag and having an opening extending transversely thereof disposed opposite the sheet withdrawal opening through the bag wall, and a plurality of separate superposed sheets extending through the opening of 55 said support and hung thereover to extend down-

wardly within the bag upon opposite sides of said support and having their free ends terminating spaced from the bottom of the bag.

2. A dispensing package for paper sheets comprising an envelope having connected front and back walls and provided with an opening extending transversely across one of said walls below the top of the envelope, a flap connected with the other wall covering said opening, a bale like supporting element secured to said other wall and having a sheet supporting portion extending transversely across the interior of the envelope opposite said opening, and a plurality of sheets superposed upon each other extending through the opening in said bale like support and hung folded over the supporting portion thereof, said sheets having downwardly extending portions upon opposite sides of the support extending downwardly within the envelope and having their free end portions terminating above the bottom of the 20 envelope.

3. In a dispensing package for paper sheets comprising a flat bag like structure having connected front and rear walls and provided with a sheet dispensing opening extending transversely 25 across the top of one of said walls, a sheet supporting element in the form of a sheet structure positioned within said bag between its front and rear walls and having a supporting edge portion extending transversely of the bag and positioned 30 opposite the sheet withdrawal opening at the top of the bag, and a plurality of separate superimposed folded sheets hung over said edge portion and extending downwardly within the bag and having their free ends terminating from 35 the bottom of the bag.

4. A dispensing package for paper sheets comprising an envelope having connected front and back walls and provided with an opening extending transversely across one of said walls adjacent 40 the top of the envelope, said envelope having a flap covering said opening, a substantially rigid sheet support within said envelope extending transversely across the interior thereof opposite 45 said opening and below the top of said flap, means positioned by a portion of the envelope supporting said sheet support for substantially free bodily movement between the front and back walls, said means providing substantial clearance between the sheet support and the top of the envelope, and a plurality of separate superposed sheets hung over said support, said sheets having portions on 50 opposite sides of the support extending downwardly within the envelope but terminating above the bottom thereof.

ALBERT R. LAWSON.
